PROPELLER FOR LOG LINE KNOTMETER

Fred W. Tann, Los Angeles, Calif., assignor to Dawn Electronics, Hawthorne, Calif.

Filed Apr. 7, 1972, Ser. No. 242,277

Term of patent 14 years

Int. Cl. D12—99

U.S. Cl. D12—214

FIG. 1 is a perspective view of a propeller for log line knotmeter, showing my new design;

FIG. 2 is a side elevational view thereof;

FIG. 3 is another side elevational view thereof;

FIG. 4 is an end elevational view thereof as seen from the left in FIG. 3; and

FIG. 5 is an end elevational view thereof as seen from the right in FIG. 3.

I claim:

The ornamental design for a propeller for log line knotmeter, substantially as shown.
